UNITED STATES PATENT OFFICE.

JOHN D. SPRECKELS, OF SAN FRANCISCO, CALIFORNIA.

ASH-HOIST.

SPECIFICATION forming part of Letters Patent No. 289,159, dated November 27, 1883.

Application filed August 18, 1883 (No model.)

To all whom it may concern:

Be it known that I, JOHN D. SPRECKELS, of the city and county of San Francisco, and State of California, have invented an Improvement 5 in Ash-Hoists; and I hereby declare the following to be a full, clear, and exact description thereof.

My invention relates to an apparatus which is especially useful for hoisting ashes from the 10 fire-rooms of vessels and discharging them overboard; and it consists, mainly, of a receiver for the material at the bottom, a line of carrying-buckets with a suitable driving mechanism, by which the buckets are caused to 15 pass through the receiver to load themselves and pass thence to the deck above, a receiving-chute or discharge-pipe leading out through the side of the vessel, and a means for keeping it clear and preventing choking, together with 20 certain details of construction, all of which will be more fully explained by reference to the accompanying drawings, in which—

Figure 1 is a perspective view of my apparatus. Fig. 2 is a vertical section of the same. 25 A is a receiver, which is fixed in the floor or hearth of the fire-room, or in any convenient place, so that when the ashes are to be discharged (which is usually about once in six hours) they may be easily raked into the receiver. Its sides may be vertical and sufficiently separated to allow the buckets to pass 30 between them. The bottom is rounded or curved, and a roller or pulley, B, is journaled to turn between the sides of the receiver, so 35 that the buckets C (which are preferably secured to a leather belt, D, to lessen the noise of working) may be carried down by the belt and dip into the receiver, so that as they rise upon the other side they will load themselves. 40 The belt D extends around a roller or drum, E, upon the upper deck, at any suitable or convenient point, and both parts of it are enclosed by a casing, F. At the top the upper drum-shaft extends out, and has a gear-wheel, 45 G, keyed to it, which is engaged by a pinion, H, upon the engine-shaft I. The shafts, gears, and the engine J, by which they are driven, are all mounted upon a frame, K, properly secured to the vessel. A discharge pipe or chute, 50 L, extends from the upper deck downward, and is curved outward, so as to discharge

through the side of the vessel, and its upper end has a hood, M, extending upward and curving partially over the upper bucket-roller, so as to insure the discharge of the contents of 55 the buckets into the chute without scattering. The chute extends down through the second deck in a nearly-vertical position, and below this deck it curves outward, so as to assume a more nearly horizontal position and pass out 60 through the side of the vessel, thus obstructing the interior space to the least extent. As the material is apt to clog when discharged through this chute, an opening or passage, N, is made into it, entering, preferably, about in 65 line with the direction of the lower portion, and a water-pipe connects with it with a valve, O, through which a body of water from the pump may be discharged through the pipe and forcibly clear it or prevent any lodgment of mate- 70 rial within it.

P is a gate or valve fitted into the discharge-chute near its outer end, and serving to close it when not in use, and thus prevent any ingress of water from the motion of the vessel or 75 the action of the sea. This valve swings in a chamber of somewhat larger diameter than the rest of the pipe, so that when open it is out of the way and leaves a clear passage. Its shaft has a lever-arm with a connecting-rod and 80 hand-lever, by which it may be opened and closed, and a curved link or rack with set-screw or pawl to hold it open or closed at will. At a point above the deck Q where the donkey-engines are usually placed I make a door, 85 R, in the side of the chute L, and a plate, S, is fitted into the chute, so that when in place it extends upward and backward from the lower edge of the door-opening at an incline. This device is used whenever it is desired to 90 hoist coal from the fire-room bunkers for the use of the donkey-engines, and the coal, being taken from the receiver A, is carried up by the buckets and discharged into the chute, flowing down to the incline-plate S, which di- 95 rectly it outward through the door-opening upon the deck. When ashes are to be hoisted, this plate is removed and the door closed. The ashes are first wet down, so as to cool them, and also prevent their injuring the ele- 100 vator-belt, after which they are raked into the receiver, and the buckets, being in motion, will

scoop them up and carry them to the top, where they discharge them into the chute, through which they escape overboard, as before described.

5 Having thus described my invention, what I claim as new, and desire to secure by Letters Patent, is—

10 1. A device for hoisting and discharging ashes, adapted to be carried by a vessel, and consisting of a receiver placed near the furnace, a chain of buckets, and a discharge-chute, connected substantially as described.

15 2. The discharge pipe or chute L, in combination with the water-pipe or flushing-passage opening into it, substantially as herein described.

3. In an apparatus for discharging ashes or material from a vessel, the discharge pipe or

chute having a hood or hopper to receive the material from an endless chain of buckets at 20 the top, and extending downward and outward through the vessel's side, in combination with the gate or valve P, by which its outer end may be closed, substantially as herein described.

25 4. The discharge pipe or chute L, with its door R, in combination with a hinged or removable plate, S, inclining upward and backward from the bottom of the door-opening, substantially as herein described.

30 In witness whereof I have hereunto set my hand.

JOHN D. SPRECKELS.
